UNITED STATES PATENT OFFICE.

IRA H. JEWELL, OF CHICAGO, ILLINOIS.

APPARATUS FOR FURNISHING DRINKING-WATER ON OCEAN-SHIPS.

1,299,002.

Specification of Letters Patent.

Patented Apr. 1, 1919.

Application filed March 1, 1919. Serial No. 280,053.

To all whom it may concern:

Be it known that I, IRA H. JEWELL, a citizen of the United States, and a resident of Chicago, in the county of Cook and State of Illinois, have invented certain new and useful Improvements in Apparatus for Furnishing Drinking-Water on Ocean-Ships, of which the following is a specification.

This invention relates to improvements in apparatus for furnishing drinking water on ocean-going ships, and refers more particularly to an apparatus in the nature of a still which is so constructed and arranged as to receive material from two sources to be used either separately or in combination to produce the drinking water. For instance, one source of the material may be vapor from the ordinary salt water evaporator at present used on ships for emergency purposes to furnish boiler make-up water and also for drinking purposes, and the other source may be fresh water from the drinking or reserve tanks carried by the ship, which tanks are filled in port to supply the ship's fresh water requirements used between ports.

Heretofore it has been the practice to have separate fresh water tanks for drinking purposes which are filled in various ports and intended to be sufficient for the voyage and also to have reserve tanks likewise filled for use of the boiler supply and other purposes of the ship where fresh water is needed, the idea of having separate tanks being that they may be flushed out to keep the drinking water tanks in a clean and wholesome condition. This practice also involves, for emergency purposes, for both the boiler make-up water and drinking water as well, that a salt water evaporator be installed on the ship and condensers provided so that both drinking water and boiler make-up supply can be produced from salt water in case of emergency, such as when the fresh water tanks are exhausted.

To accomplish this condensing arrangement there have usually been built in the ships separate condensers for the boiler make-up water as supplied from the salt water evaporator usually known as the auxiliary condenser, which contemplates cooling down this vapor to about 120° Fahrenheit, so they can preserve all possible heat in the boiler make-up water, and then to have a separate condenser to fill the drinking water tanks which will permit the temperature to be reduced to the lowest possible

degree. This condenser on shipboard for drinking purposes has been termed in marine practice "distiller" and is usually hung up in a high point on the ship so that the outlet can deliver the water by gravity into the drinking water tanks.

It is general practice for the ship to have a pump which takes the water from the drinking water tanks and delivers it to a small gravity head tank located on the top house deck and then to run a distribution line from the gravity head tank to the drinking taps. Owing to the stale condition of the ship's reserve tank's fresh water supply, as well as the drinking tank's supply, together with the impurities which settle in them, which occur from the several days of voyage at sea, it is practically impossible that even a filtered water of such normal purity as would be satisfactory for a municipality can retain this purity for a long voyage, thereby developing bacterial growths and odors which renders same unfit for drinking purposes, and even likely to produce disease.

When vapor from the salt water evaporator must be condensed for drinking water, it is generally found even more objectionable than any condition of the fresh water supply above stated. Sea water contains so many minerals and gases in solution that its condensed vapor carries them largely with it so that a palatable and satisfactory quality of drinking water is not produced unless a condition, often provided, such as aeration, frequently with special air pumps, and that it also be filtered, and even then it often requires a standing period of 24 hours. It may occur that the salt water evaporator foams over, as it frequently does do, and that salt is carried along with the vapor even when foaming does not occur which makes brakish water that is conducted to the drinking tank supply.

One purpose of the present invention is to provide an apparatus which may be used in a system for obtaining drinking water from several different sources heretofore not utilized so that the system can be made more flexible in this regard and the emergency use of the salt water vapor greatly reduced.

Another purpose of the invention is to provide a single unitary apparatus which can do the joint work of receiving vapor from the salt water evaporator in emergency and reliquefy, aerate and filter it, and, with the same apparatus, to take any of the

ship's fresh water supply and evaporate, liquefy and filter it; and the same apparatus can operate upon both salt water vapor and fresh water to produce a product which will 5 be a combination of the salt and fresh water, a better product than if the salt water vapor should be used alone, the desirability being that when the ship is running low with its 10 fresh water supply it may be supplemented by the use of the salt water vapor in the manner stated.

I have shown in the drawing one embodiment of my apparatus for illustrating the invention, but it will be understood that 15 the invention is not restricted to the details herein shown, except as to claims where said details are specifically set forth or imposed by the prior art.

In the drawings, Figure 1 is a side elevation, partially in section to show interior parts.

Fig. 2 is a side elevation as viewed from a plane at a right angle to the plane of Fig. 1.

Figs. 3 and 4 are transverse sections on the respective lines A—A and B—B of Figs. 2 and 1.

Fig. 5 is a detail of one of the condenser tubes shown in the manner of fitting them 30 to the top and bottom manifold plates of the distiller chamber.

Fig. 6 is a detail of a wrench employed for removing the condenser tubes.

Fig. 7 is a cross section on the lines C—C 35 of Fig. 6.

As shown in the drawings 10 designates the distiller chamber, 11 the evaporator chamber covered by a hood 12 which is centrally apertured and closed by a cover 13. 40 The condenser tubes 14 are contained within said distiller chamber and extend through the top and bottom manifold heads 15 and 16 of the distiller chamber. Said condenser tubes extend beyond the upper manifold 45 head through the condenser chamber dome and into the cover 13 and are open at their upper end. The portion of the condenser tubes above the manifold head 15 extend through an upright casing 18 of the approximate diameter of the distiller chamber, which casing forms a chamber 19 to receive the salt water vapor and to prevent intermixing of the salt water vapor with the contents of the fresh water evaporator 55 chamber. The cover 13 is provided within the dome with a depending perforated guard 20 which surrounds the upper ends of the condenser tubes and which terminates short of the upper end of the casing 18 to 60 provide a space 21 for the passage of steam from the fresh water evaporator chamber to the upper ends of the condenser tubes.

Said condenser tubes terminate at their lower ends in reduced drip ends 22 which 65 extend through packing glands in the lower

manifold head into a filter chamber 23 that contains a body of granular filter material, such as charcoal, supported on a perforated plate, below which is formed a reservoir 24, having outlets 25 and 26, the lower one for direct service and the other for overflow and vent. Condensing water is directed to the filter chamber through an inlet 27 and is discharged therefrom through an outlet 28. 30 designates the valved salt water vapor supply pipe through which vapor is supplied to the vapor receiving chamber 19. 31 designates the valved fresh water inlet pipe through which fresh water is conducted to the lower part of the evaporator chamber 11, and 32 designates an overflow pipe, connected to the upper end of an open riser 33 which is connected at its lower end to the inlet pipe 31; the connection between the riser and the overflow pipe being at a level 85 to submerge the fresh water evaporating coil 34 in the evaporating chamber 11 and also to maintain a proper water seal against pressure of the salt water vapor. 35 designates the steam inlet for the coil 34 and 36 the trapped outlet thereof. 37 designates a valved drain for the vapor receiving chamber 19 to draw any water that may accumulate in the bottom thereof, together with the salt entrained with the vapor released in said chamber by reason of the reduction of vapor velocity when it enters said chamber from the inlet 30.

In operation, assuming the apparatus to be used to condense salt water vapor, the 100 vapor is conducted to the lower end of the chamber 19 through the pipe 30 and rises to and enters the upper ends of the condenser tubes in the cover 13. Condensing water, preferably sea water under pressure, 105 is passed through the distiller chamber in contact with the outer walls of the condenser tubes and is discharged overboard. The water condenses the vapor, the resulting water passing downwardly through the 110 tubes and into and through the filter chamber and passes through the filtering medium into the reservoir 24 from whence it is withdrawn for use. The joint between the condenser tubes and the upper manifold head 115 is made to prevent passage of the sea water from the distiller chamber to the evaporator chamber and thereby contaminate the water in the latter chamber. As shown said joint is formed by sweating a bushing 39 on the 120 tube and taper threading it to engage taper threads in the manifold head.

When distilling fresh water, and assuming for the purpose of this statement that fresh water alone is to be distilled, the valve in 125 the salt water vapor pipe 30 is closed and the valve in the fresh water inlet pipe 31 is opened. Water is supplied to the evaporator chamber and submerges the evaporating coil 34 thereof, the level of the water being de- 130

terminated by the level at which the overflow pipe 32 is connected to the open riser 33. Steam from the ship's boiler or other suitable source is passed through the coil 34 and evaporates the water, the vapor rising through the opening 21 between the guard 20 and casing 18, and also through the perforations of the guard, into the cover to the upper ends of the condenser tubes. The vapor passes downwardly through the tubes and is condensed, the resulting water passing through the filter and into the reservoir 24 below.

When it is desired to mix the vapor from both salt and fresh water supplies, and thereby produce drinking water from both sources, the valves of both the salt water vapor pipe and the fresh water pipe and of the steam inlet to evaporating coil are opened. The salt water vapor is then commingled with the fresh water vapor in the condensing tubes. The relative opening of the valved salt water vapor and steam inlets will determine the proportion of the mixture of the two constituents, so that it thereby becomes practicable to blend the two vapors to produce a good drinking water while, at the same time using a lesser portion of the fresh water, thereby economizing the fresh water in the event the fresh water tanks are running low.

The overflow pipe 32 maintains, not only the level of the water in the evaporator chamber, but also furnishes means by which water condensed in the evaporator chamber may be conducted back into the fresh water tanks, thus producing thereby an additional supply of fresh water when operating on salt water vapor.

A pipe 38, open to atmosphere, is connected to the filter chamber 28, when employed, or the reservoir 24 when the filter chamber is not employed, for the purpose of permitting the apparatus to operate under atmospheric conditions, such as to take in atmosphere to the condensing tubes and assist aeration of the water therein in event that vacuum should be created in the tubes when the steam is condensed, so the atmospheric oxygen can unite with the condensed water at the instant action of its liquefaction; it being understood that not enough steam or vapor will enter the tubes to fill the void or vacuum created when vapor is condensed because the steam enters the tubes under only a few ounces of pressure. The water level seal shown in Fig. 1 provides for only a few ounces of pressure. On the other hand, this pipe 38, open to atmosphere, furnishes means for escape of non-absorbable gases which come over with the steam or vapor into the condenser tubes that would tend to build up a pressure in the apparatus and thereby prevent it working under normal atmospheric conditions; the idea

being that oxygen which is carried over by the steam or vapor will combine with the distilled water and that other gases will be discharged through the pipe 38. Just which of these two conditions causes the vacuum 70 or pressure will, of course, depend upon the character of the steam or vapor which in turn involves the character of the water supply from which it is produced.

The condenser tubes 14 may be separately 75 removed when the cover 13 is removed, by a wrench comprising a hollow shank 40 provided at its lower end with jaws 42 to enter sockets 43 in the bushing 39, the shank having a guide collar 41 which surrounds said 80 jaws. The hollow wrench is long enough to be slipped down over a tube 14 to engage its jaws with the sockets 43 and may be turned by a cross-rod that extends into openings in the upper end of the shank. 85

I claim:

1. Apparatus for distilling fresh water and condensing salt water vapor comprising a complete operative evaporator and condenser for distilling the fresh water, including heating means for the evaporator and provided with a vapor connection independent of said heating means adapted to deliver salt water vapor to the apparatus to condense the vapor. 95

2. Apparatus for distilling fresh water and condensing salt water vapor comprising an evaporator for the fresh water, provided with heating means, and provided with a vapor connection independent of said heating means to deliver salt water vapor thereto, and a condenser to receive vapor from both said evaporator and said connections. 100

3. Apparatus for distilling water and condensing vapor comprising an evaporator 105 having a fresh water supply and a vapor receiving chamber having an independent salt water vapor supply, combined with a condenser having tubes which extend through said receiving chamber to receive 110 vapor from both said evaporator and said chamber.

4. Apparatus for furnishing distilled drinking water on ocean-going ships comprising means for evaporating, condensing, aerating and filtering the ship's fresh water supply, including heating means for the evaporator, combined with means whereby vapor supplied independent of said heating means can be treated by the same condensing, aerating, and filtering means. 115

5. Apparatus for furnishing drinking water on ocean-going ships from the ship's fresh water supply and vapor from the ship's salt water evaporator, comprising a condenser, a fresh water evaporator, including heating means therefor, and having means to direct its vapor to said condenser, a supply pipe adapted to deliver water from the ship's fresh water supply to the evaporator, 125 130

connections independent of said heating means adapted to supply salt water vapor from the ship's salt water evaporator to said condenser, and a filter connected to the discharge of said condenser.

6. Apparatus for distilling fresh water and condensing salt water vapor comprising a complete operative evaporator and condenser for distilling the fresh water, including heating means for the evaporator, and provided with a vapor connection independent of said heating means adapted to deliver salt water vapor to the apparatus to condense the vapor, and means for aerating the water in the condenser.

7. Apparatus for furnishing drinking water on ocean-going ships from the ship's fresh water supply and vapor from the ship's salt water evaporator, comprising a condenser, a fresh water evaporator, including heating means therefor, having supply connections to deliver water from the ship's fresh water supply to the evaporator and constructed with means to direct its vapor to the condenser, means, independent of said heating means for supplying salt water vapor from the ship's salt water evaporator to said condenser, and air connections with the device whereby the condensate is aerated by air drawn into the condenser by the vacuum created at the instant action of condensing said vapors.

8. Apparatus for distilling water and condensing vapor comprising an evaporator and a separate vapor receiving chamber centrally therein, combined with a condenser having tubes which extend through and beyond said chamber to receive vapor from both said evaporator and said chamber.

9. Apparatus for distilling water and condensing vapor comprising an evaporator having a dry dome and a separate vapor receiving chamber centrally therein, combined with a condenser having tubes which extend through the said chamber and to the dry dome to receive vapor from both said evaporator and said chamber.

10. Apparatus for distilling water and condensing vapor comprising an evaporator having a dry dome and a separate vapor

receiving chamber centrally therein, combined with a condenser having tubes which extend through the said chamber and to the dry dome to receive vapor from both said evaporator and said chamber, said dome being provided around the receiving ends of said tubes with a splash guard.

11. Apparatus for distilling water and condensing vapor comprising an evaporator, a heating coil and a water supply pipe therefor, a vapor receiving chamber open to said evaporator, a source of vapor supply for said chamber, independent of said heating coil, said supply pipe being provided with overflow pipe connections adapted to maintain a uniform water level in the evaporator and a water seal against escape of the vapor, and a condenser in communication with said evaporator and chamber.

12. Apparatus for distilling water and condensing vapor comprising an evaporator, including heating means, a vapor receiving chamber open to said evaporator, a source of vapor supply for said chamber independent of said heating means, said evaporator provided with overflow pipe connections to maintain a water seal against the escape of the vapor, and a condenser in communication with said evaporator and chamber, the outlet of said condenser discharging into a chamber therebelow open to atmospheric pressure.

13. Apparatus for distilling water and condensing vapor, comprising an evaporator, including heating means therefor, vapor supply means independent of said heating means, said evaporator being provided with means to maintain a water seal against escape of vapor, a condenser to receive vapor from said evaporator and said supply means and adapted to receive condensing water from a source separate from the evaporator supply, and means in communication with the outlet of said condenser to maintain the operation of the apparatus under atmospheric conditions.

Signed at Washington, D. C., Feb. 27th, 1919.

IRA H. JEWELL.
